UNITED STATES PATENT OFFICE

ÉVA MARLER, OF OKLAHOMA CITY, OKLAHOMA, ASSIGNOR TO OSCAR JOHN GRACE
AND ESTELLA F. GRACE, BOTH OF OKLAHOMA CITY, OKLAHOMA

OIL WELL CONTROL

Application filed January 5, 1932. Serial No. 584,843.

This invention appertains to new and useful improvements in means for controlling oil wells and more particularly to a novel machine whereby oil or gas flow can be controlled in a quick, convenient and effective manner.

The principal object of this invention is to provide a machine wherein a wild oil well can be shut off in a minimum length of time and without endangering the lives of those working in the operation.

Another important object of the invention is to provide a shut-off device for flowing oil wells, and means whereby the said shut-off device can be operated remotely in a direction laterally of the well.

Other important objects and advantages of the invention will become apparent to the reader of the following specification.

20 In the drawings:—

Figure 1 represents a side elevational view of the apparatus in its entirety.

Fig. 2 represents a horizontal sectional view through the carrier with certain parts removed to disclose the adjustable truck.

Fig. 3 represents a fragmentary vertical sectional view through the means for actuating the well stopper device.

Fig. 4 represents a fragmentary vertical sectional view through the truck.

Fig. 5 represents an enlarged vertical sectional view through the means connecting the truck to the chassis.

Fig. 6 represents a fragmentary longitudinal sectional view through one of the extensible rods.

Fig. 7 represents a fragmentary vertical sectional view through the stopper operating means.

Fig. 8 represents a top plan view of the cross member of the stopper operating means.

Fig. 9 represents a fragmentary vertical sectional view through the stopper device in an oil well casing.

Fig. 10 represents a fragmentary vertical sectional view through the wedge-shaped expander.

Fig. 11 represents a top plan view of the packing ring.

Fig. 12 represents a cross sectional view taken substantially on line 12—12 of Fig. 3.

Fig. 13 represents a cross sectional view of the screw head of the stopper device.

Fig. 14 represents a side elevational view 55 of the packing ring.

Fig. 15 represents a cross sectional view of the anchor.

Referring to the drawings wherein like numerals designate like parts, it can be seen 60 that the machine involves three main features consisting of the stopper device, generally referred to by numeral 5; the stopper operating mechanism generally referred to by numeral 6, and the transporting machine 65 generally referred to by numeral 7.

First taking up the description of the stopper device 5, attention is directed particularly to Figs. 1, 9, 10, 11, 12, 13, 14 and 15. In Fig. 9, it will be observed that numeral 8 denotes an oil well casing into which the stopper device 5 is to be inserted. The stopper device includes a spear head 9, the lower portion *a* of which is tapered conically, while the upper portion *b* is cylindrical and has the bore 10 extending longitudinally therein to merge with the diametrically disposed bore 11 opening through opposite sides of the spear head 9.

Complemental to this spear head 9 is the 80 anchor 12 which is generally of cylindrical shape, but divided into four (more or less) longitudinally extending sections *c*, *d*, *e*, and *f*. These sections *c* to *f* inclusive have their 85 opposed sides formed with recesses 13 in each of which is an eye 14, and between complementary eyes are connected the springs 15, which obviously serve to tensionally connect the sections together in the cylindrical formation obviously necessary to prevent disposure into the oil well casing 8.

This anchor 12 has a longitudinally extending bore 16 therein and the upper ends of the sections *c* to *f* inclusive are bevelled as at 17, 95 while their outer sides are provided with ratchet-like ribs 18 capable of biting into the inner side of the oil well casing 8 and in the manner substantially shown in Fig. 9.

The third element of importance in this stopper device is the packing ring shown 100

clearly in Figs. 11 and 14. This ring consists of the disk 19 having the central opening 20 and this disk 19 is split irregularly as at 21 to provide the interlocking tongues 22 and 23, which interlock in the manner similar to certain types of piston rings. The periphery portion of this packing ring flares outwardly on both its top and bottom sides to provide the ring or annulus 24, it being observed in Fig. 9, that the flare of this ring is in the nature of a bevel both on the top and bottom sides of the disk, so that the upper and lower ends of the screw head 9 and anchor 12 respectively, can ride against this ring portion 24 when contracted to expand this particular portion of the packing ring against the inner side of the casing 8 to prevent obviously, upward flow of oil or gas in the casing.

To effect this binding disposition of the packing ring, a cylindrical-shaped expander 25 is employed and is tapered at its lower end to engage the beveled inner side of the sections of the anchor 12. The upper end of this expander merges with the lower end of the elongated tube 26 which is substantially less in diameter than the expander 25, and is provided with a longitudinally extending smooth rack 27.

The expander 25 is provided with a longitudinally extending threaded bore 28 for receiving the threaded portion 29 of the elongated control rod 30 which extends longitudinally through the tube 26 and longitudinally through the anchor 12 and spear head 9, as well as through the packing disk 19. The lower end of this rod 30 is secured by the collar 31 and pin 32 to the spear head 9, the collar and pin being located at the lower end of the bore 10 and within the bore 11. (See Fig. 9).

Obviously, when the rod 30 is rotated in a given direction, the expander 25 will be urged against the beveled ends of the anchor sections at the same time an upward pull is exerted on the spear head 9. In this manner, the contraction of the spear head 9 and anchor 12 will expand the packing ring against the casing 8 while the ratchet-like ribs 18 are biting into the casing to anchor the packing ring in the position substantially shown in Fig. 9.

Referring now particularly to Figs. 1, 3, 8, and 12, it can be seen that the aforementioned tube 26 extends upwardly through the barrel 33, which at its upper end supports the shaft 34 carrying a gear 35 which meshes with the rack 27 on the tube 26. The barrel 33 is provided with trunnions 36—36 extending in opposite directions, and these have their ends journaled in the bearings 37, which bearings are supported by the uprights 38 at the end of the transporting machine generally referred to by numeral 7.

One of the trunnions 36 has a gear 38 secured thereto and with which the worm 39

meshes. This worm 39 is on the shaft 40 which is supported by the bracket 41 projecting from one of the forward posts 38 on the machine 7.

As is clearly shown in Fig. 3, the upper end of the tube 26 is reduced and disposed through an opening 42 at the intermediate portion of the cross member 43. Each end of this cross member 43 is provided with an apertured ear 44 and as is clearly shown in Fig. 3, the upper end of the rod 30 which extends longitudinally thru the tube 26 is provided with a reduced extension 45 of polygonal shape in cross section for slideable disposition through a correspondingly shaped opening in the gear 46, which gear is supported against the upper end of the tube 26 by the bracket 47, where it is constantly in mesh with the worm gear 48 carried by the shaft 49 which is supported by the means 50.

Each of the gears 44 is provided with a ring 51 and from each of these rings 51 extends a sprocket chain 52 which are trained under the sprocket wheels 53, which are supported at the forward end of the chassis frame 54 of the transporting machine 7.

As is clearly shown in Fig. 7, the cross member 43 is secured to the tube 26 by a set screw 55.

The transporting machine 7 includes the aforementioned chassis frame 54, the aforementioned forward post 38 and the rear post 56, as well as intermediate posts 57 which are connected by the rails 58. The chassis frame 54 is supported by a two-wheel truck, and as is shown in Fig. 22, this truck includes a frame 59 which supports the transversely extending shafts 60 carrying at their ends, the rollers 61 for riding engagement with the under sides of the chassis frame bars *g* and *h*.

The frame 59 is connected to the axle 62 by the semi-elliptical springs 63—63 and as shown in Fig. 4, the axle 62 is provided with the tired wheels 64—64. As is apparent in Fig. 5, the bars *g* and *h* of the frame 54 are of I-type, and guide units are provided on the truck for engagement with these bars. Each of these guide units or assemblies consists of a pair of bracket members 65—66 each provided with a converging extension for engagement with the lower flange of the corresponding bars *g* or *h*, these arms being secured to a boss or block 67 on the frame 59 in the case of the arm 66, and in the case of the arm 65, directly to the frame 59. Thus the truck is positively connected in a slideable manner to the chassis frame 54.

A cable 68 connects to the rear end of the truck, whereby the truck can be pulled rearwardly, while a cable 69 connects to the forward end of the truck and is trained over a forwardly located pulley 70 on the machine 186

7 to extend rearwardly, whereby the truck can be moved forwardly.

Obviously, the cables 68 and 69 extend to a remote point, where they can be optionally operated to move the truck in the desired direction. Furthermore, a suitable coupling 71 connects the machine 7 to a tractor or the like, whereby the machine can be easily moved from one point to another.

The rear end portion of the machine 7 is provided with the guides 72 for rotatably supporting the shafts 73-74 and 75. The shaft 73 is connected by the universal joint 76 to the shaft 77, which in turn is connected by the universal joint 78 to the worm shaft 49, whereby the rod 30 of the stopper operating mechanism can be controlled.

The shaft 74 sticks by the universal joint 78 to the shaft 34, whereby the gear 35 to be actuated to move the aforementioned tube 26, whereby the stopper device can be elevated or lowered with respect to the casing 8.

The shaft 75 is connected at its forward end by the universal joint 79 to the shaft 40 bearing the worm 39 and obviously by actuating this worm 39, the barrel 33 can be tilted to the desired position for insertion of the stopper 5 into the well casing 8.

Cables 80 connect to the lower ends of the sprocket chains 52, and obviously, these cables 80 can be connected to suitable means whereby considerable force can be exerted on the cross member 43 for driving the stopper device 5 into the well casing 8 against the enormous pressure of the issuing of fluids, whether it be oil or gas.

It is to be understood, that any one of the aforementioned shafts and particularly the shaft 77 can be of the slip type, consisting of the tubular section *k* provided with the polygonal-shaped opening extending longitudinally therein, for slidably receiving the polygonal-shaped section *L*. Such a type of shaft is notoriously old, and is not in itself part of the present invention.

Furthermore, it is to be understood that the shafts 73, 74 and 75, as well as the truck control cables 68 and 69, can extend to any remote point away from the machine 7, where the operator for the same will be safely removed from the oil well, which when wild is frequently on fire and cannot be approached.

Furthermore, it is to be understood, that the transporting machine shown in Fig. 7 can be considerably longer than that represented in the drawings, and that various changes in the shape, size and materials may be resorted to in the construction of this machine, without departing from the spirit and scope of the invention as claimed hereinafter.

Having thus described my invention, what I claim as new is:—

1. A machine of the character described comprising a frame, a truck, means whereby the truck can be adjusted longitudinally be-

neath the frame, a well closing device, and means on one end of the frame whereby the well closing device can be driven into a well.

2. A machine of the character described comprising a frame, a truck, means whereby the truck can be adjusted longitudinally beneath the frame, a well closing device, means on one end of the frame whereby the well closing device can be driven into a well, and remotely controlled means whereby the truck can be adjusted beneath the frame.

3. An oil well stopper device comprising a spear head, an expansible anchor, an expander for the anchor, and expansible packing means between the anchor and the spear head.

4. An oil well stopper device comprising a spear head, an expansible anchor, an expander for the anchor, expansible packing means between the anchor and the spear head, and means for urging the expander against the anchor to expand the anchor and simultaneously to contract the anchor and spear head against the packing.

5. An oil well stopper device comprising a spear head, an expansible anchor, an expander for the anchor, expansible packing means between the anchor and the spear head, means for urging the expander against the anchor to expand the anchor and simultaneously to contract the anchor and spear head against the packing, said packing being provided with a beveled portion against which the anchor and spear head can ride.

6. In combination, an oil well stopper, a tube extending from the stopper, a rack on the tube, a remotely controlled gear meshing with the rack, the lower end of the tube being provided with expanding means, and means on the stopper adapted to be expanded by the said expanding means, a screw threaded rod extending longitudinally through the tube for operating the expanding means, and means at the upper end of the rod whereby the rod can be rotated independently of the tube.

In testimony whereof I affix my signature.
EVA MARLER.
